UNITED STATES PATENT OFFICE.

WILLIAM H. DE FORD, OF PITTSBURG, PENNSYLVANIA.

BUNION-GUARD.

933,423.

Specification of Letters Patent.

Patented Sept. 7, 1909.

Application filed September 3, 1908. Serial No. 451,502.

To all whom it may concern:

Be it known that I, WILLIAM H. DE FORD, a citizen of the United States, and residing in the city of Pittsburg, in the county of Allegheny and State of Pennsylvania, have invented or discovered new and useful Improvements in Bunion-Guards, of which the following is a specification.

My invention, generally speaking, consists of new and improved means for relieving and curing bunions or distortions of the second joint of the great toe of a human foot.

Bunions are usually caused by improperly fitting or designed shoes which result in bending the great toe inwardly toward or overlapping the adjacent toes from its second joint, forcing out the joint into a prominent protuberance against which the shoe presses and which results in a very painful lameness. This protuberance is visible through the shoe and gives the foot a very unsightly appearance in addition to crippling the sufferer.

My invention consists of a horizontally rigid plate partially severed or cut across, so that a natural bending of the foot in walking is permitted. The plate is worn in the shoe and means are provided for securing the toe in its natural position, thereby reducing the protuberance of the joint and restoring the natural contour of the foot. By curving the lateral, outside edge of the plate, I protect the toe and joint against shoe pressure.

Many other novel and advantageous features will appear from the following description.

In the accompanying drawings, Figure 1 is a perspective of a right foot fitted with my invention; Fig. 2 is a bottom plan view of a left foot; Fig. 3 is an enlarged bottom plan view of my invention removed from the foot and Fig. 4 is a top plan view of the same, while Fig. 5 is a cross-section along the line V—V in Fig. 4.

The following is a description of the drawings:—

1 represents a right foot of a human being; 2 the second joint of the great toe which is supposed to be distorted into a bunion.

3 is a plate, preferably of some substantial material such as spring steel. Said plate is arranged to fit under the sole of the foot within the shoe and may extend partially or

wholly across the sole of the foot as may be desired. The said plate 3 is bent upwardly and inwardly to inclose the second joint 2 as at 4 in Figs. 1, 3 and 4, thus protecting 60 said joint from the shoe and assisting the means hereinafter described to reduce the bunion and maintain the joint in natural alinement. The said plate 3 is also bent upwardly and slightly inwardly to form portion 5 which embraces the great toe as shown in Fig. 1. The metal of plate 3 is cut as at a before bending or stamping into the shape shown so that when bent up the portions 4 and 5 overlap somewhat and a 70 natural bending action is thus provided in plate 3. Of course any other convenient character of bending mechanism may be substituted for the means shown but that above described has proven eminently satisfactory and is very inexpensive.

6 is a loop of leather or other suitable, flexible material, attached to portion 5 of plate 3 and adapted to embrace the great toe of the wearer, an aperture 7 being provided to accommodate the soft corn which usually appears on the inner side of a great toe in the case of a bunion.

8 is a lining for plate 3, preferably of hard rubber suitably attached to protect the 85 foot from the plate and to prevent rust. Any other suitable lining, attached in any convenient manner, may be substituted, if desired.

It is evident that the plate 3 is practically 90 rigid in a horizontal direction so that the great toe secured in loop 6 cannot slip or move over toward the other toes into the unnatural position which it is desired to correct, which return movement would 95 inevitably result if the great toe be not securely anchored in the natural alinement. As long as the great toe is held in proper alinement, the bunion can be reduced by the consequent relocation of the bones of the 100 second joint in their natural relative positions. This lack of means for anchoring the great toe in its proper alinement has been a cardinal defect in previous devices of this general character.

Continuous use of my invention, maintaining the great toe in proper alinement and thus gently forcing the second joint back into its natural position eventually results in curing the bunion and restoring the foot to its proper contour. The provision for vertical bending in the plate al-

lows the foot to bend naturally in walking or in other use, not however, in any way impairing the horizontal rigidity of the device or permitting the great toe to escape 5 from its proper position.

It will of course be understood that the device intended for the left foot will be the reverse of the device illustrated and that different sizes and shapes will be provided 10 to suit the feet of the wearers.

Although, for the sake of clearness, I have minutely described the practical construction shown in the drawings, I do not wish to limit myself thereby, but claim broadly:—

15 1. A bunion guard consisting of a horizontally rigid plate partially severed and disconnected to provide a vertical bending action adjacent to the first joint of the toe and means for securing the toe in proper 20 alinement in said plate.

2. A bunion guard consisting of a plate of rigid material adapted to be interposed between the sole of the foot and the shoe, a curved portion of said plate being adapted to protect the bunion from shoe pressure and 25 a second curved portion of said plate being adapted to protect the end portion of the toe from shoe pressure, the material of said plate between said curved portions being partially severed and remaining disconnected, the said curved portions being permitted to overlap, whereby a vertical bending action is provided in said plate, for the purposes described.

Signed at Pittsburg, Penna., this 1st day 35 of September, 1908.

WILLIAM H. DE FORD.
